(57) **CLAIM**

The ornamental design for an LED garden lamp, as shown and described.

DESCRIPTION

FIG. 1 is a perspective view of an LED garden lamp showing the new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is another perspective view thereof.

The broken lines in the figures show portions of the LED garden lamp, which are for illustrative purposes only and form no part of the claimed design.

1 Claim, 8 Drawing Sheets
